UNITED STATES PATENT OFFICE.

HUGH MCKENZIE, OF CARO, MICHIGAN.

SPARK-ARRESTER.

SPECIFICATION forming part of Letters Patent No. 241,875, dated May 24, 1881.

Application filed March 23, 1881. (No model.)

To all whom it may concern:

Be it known that I, HUGH MCKENZIE, of Caro, in the county of Tuscola and State of Michigan, have invented an Improved Spark-5 Arrester, of which the following is a specification.

The nature of my invention relates to certain new and useful improvements in the construction of devices attached to a smoke-stack, 10 for the prevention of the passage of sparks out of said stack at its top.

The invention consists in the novel and peculiar construction of the parts, and their combinations with each other and with a smoke-15 stack, whereby sparks are arrested and extinguished in the stack, and discharged therefrom by a flow of water, as more fully herein-after described.

Figure 1 is a vertical central section. Fig. 20 2 is a plan with the cap of the stack removed. Fig. 3 is a cross-section on the line 33 in Fig. 1.

In the accompanying drawings, which form a part of this specification, A represents a section of a smoke-stack of a portable engine, 25 mounted by a cap or hood, B, whereby an enlarged chamber is formed around the discharge end of the stack, the latter terminating in a double and inclosed deflector, C, the only outlets from which are the openings a, whereby 30 the products of combustion are arrested and thrown vertically downward into the hood. The shape of this double deflector is shown in Fig. 1, and its sides are inclosed, and it has a central opening in the bottom, coincident and en-35 gaged with the top of the stack.

D is a water-pipe, with one end projecting

through the wall of the hood, and, when in use, designed to be connected with any suitable source of supply, while that portion of the pipe within the hood extends spirally downward along its inner side, as shown. 40

E is an exit-pipe leading out of the hood near its conjunction with the stack.

F is a smoke-discharge pipe through the top of the hood, with its lower end projecting 45 downward within the hood.

In practice the products of combustion pass from the top of the stack into the double deflector, and the cinders and sparks are arrested and thrown down through the openings a into 50 the hood, while the smoke itself will, after leaving the deflector, pass upward to the exit. As the sparks fall they are thrown into the water from the pipe D, and carried with such water out of the hood, through the exit-pipe E. 55

What I claim as my invention is—

1. In combination with the smoke-stack A and the hood B, tightly fitting the stack A at its lower end, the inclosed double deflector C, provided with two separate curved passages, a 60 a, and having straight flat sides, substantially as and for the purpose specified.

2. In combination with the stack A, hood B, and inclosed deflector C, having separate passages a a, the curved inclined inlet-pipe D, 65 adapted to cause the water to flow around the smoke-stack, and the outlet E, substantially as described.

HUGH MCKENZIE.
